FILTER

Ronald A. Bailey, Bletchley, England, assignor to
Wipac Filtration Limited, Bletchley, England,
a company of Great Britain

Application May 2, 1949, Serial No. 90,923
In Great Britain May 12, 1948

8 Claims. (Cl. 210—181)

1

This invention relates to filters for liquids, and it is especially but not exclusively concerned with filters for fuel supplied to internal-combustion engines and for lubricating oil in pressure circulation systems of such engines and other machines.

An object of this invention is to provide a filter which is simple, efficient, inexpensive and easily reconditioned and which can be made in various capacities with standard parts.

Another object is to obviate the need for sealing washers fitting against the filtering elements.

Another object is to provide an improved filtering element.

According to this invention, a liquid filtering element consists of a perforated frusto-conical annulus of stiff sheet material having projections on its inner surface and an annulus of sheet filtering material fitted as a lining to the perforated annulus and held in place by two annular flanges on the perforated annulus overlying the radially inner and outer borders of the filtering annulus. The perforated annulus may be for example a sheet metal pressing, the projections being concentric pressed annular ridges. The filtering annulus may consist of a layer of wire gauze adjacent to the perforated annulus and acting as a support for a layer of felt or other easily pliable sheet filtering material.

Also according to this invention, a filter for liquid includes a stack of at least one pair of frusto-conical filtering elements as hereinbefore specified and pressed together base to base by means of a tie passing co-axially through the stack and having two annular abutments engaging the radially inner borders of the end elements of the stack, a vessel enclosing the stack, and two liquid ducts communicating respectively with the enclosed spaces inside and outside the stack.

The tie may be formed by a tubular duct which fits the central apertures in the elements and so ensures their co-axial relationship and which has one or more ports communicating with the space within each pair of elements.

In one form of the improved filter, the tie is a tubular screw engaged in an internally screw-threaded port in a body member, the said two abutments being formed respectively on the body and on a head on the screw. In another form the tie is a tube having flanged ends forming the said abutments.

Further according to this invention a filter for liquid includes a stack of at least one pair of frusto-conical filtering elements as hereinbe-

2

fore specified and pressed together base to base by means of a perforated tubular tie having one end closed, said tie passing co-axially through the stack and having two annular abutments engaging the radially inner borders of the end elements of the stack, a vessel enclosing the stack, liquid inlet and outlet ducts communicating respectively with the open end of the tie and with the enclosed space outside the stack, and biasing means urging the stack axially in such a direction as to close the junction between the inlet duct and the open end of the tie.

Two embodiments of the invention as applied to a fuel-oil filter and to a full-flow lubricating oil filter for internal combustion engines will now be described, by way of example, with reference to the accompanying drawings wherein:

Figure 1 is a section in elevation of a fuel-oil filter taken along the line 1—1 in Figure 2.

Figure 2 is a view in elevation of the filter to the same scale as in Figure 1.

Figure 3 is a diagrammatic section of one of the filtering elements appearing in Figures 1 and 2 and drawn to a larger scale.

Figure 4 is a view in elevation of the same filtering element drawn to a scale intermediate between those of Figures 1 and 3.

Figure 5 is a diagrammatic section in elevation of a full-flow lubricating oil filter according to the invention, and

Figure 6 is a section taken along the line 6—6 in Figure 5.

The filter body 10 is a substantially circular die-casting having diametrically opposed radial inlet and outlet sockets 11 and 12 respectively. The body is mounted with its axis vertical and may be attached to a suitable support by screws passing through screw holes 13 and 14 in a bracket 15 which is integral with the filter body 10.

A sealing washer 16 is located in an annular seating in the underside of body 10. A metal or glass bowl 17 is held with its edge pressing on to the sealing washer 16 by means of a wire stirrup 18 having its ends pivoted in housings 19 and 20 integral with the body 10.

The bowl is pressed against the sealing washer by a nut 21 working on a jacking screw 22 which has a slotted portion 23 embracing a flat on the stirrup 18. The nut 21 has an extension 24 forming an annular groove whose sides embrace the borders of an aperture in the bottom of a cup 25 against which the nut 21 presses; the extension retains the cup on the nut when the cup is not under pressure from the nut. The edge of the cup 25 surrounds a depression 26 in the bowl 17; the de-

pression serves to prevent movement of the cup 25 transversely to the axis of the filter whilst the nut 21 is tightened. The lip of the bowl 17 is narrow and consequently little pressure is required to seat it on the sealing washer 16 so as to give a tight seal. The outlet socket 12 communicates by means of a passage 27 with an internally threaded hollow cylindrical boss 28 projecting downwards from the middle of the body. The inlet socket 11 communicates with a port 29 in the under side of the body between the outlet boss 28 and the sealing washer 16.

A tubular tie 30, having a diameter of $\frac{5}{8}$ in., which is smaller than the external diameter of the tubular boss 28, is provided at its upper end with a screwed spigot 31 engaged in the boss. At the lower end the tie is closed by a hexagonal head 32 providing a flat annular facing 33 on its upper side. The filtering elements are identical, and any desired even number is provided, according to the capacity of the filter. Each element consists of a frusto-conical pressing 34 of soft sheet aluminum $2\frac{1}{2}$ in. in diameter and 0.015 to 0.018 in. thick, the central aperture being $\frac{5}{8}$ in. in diameter. The apex angle of the cone is 158° . Two annular ribs 35 and 36 of arcuate section and $\frac{3}{64}$ in. deep are pressed in the cone so as to project on its inner surface. Each of the three annular zones 31, 38 and 39 has eight perforations 40 of $\frac{1}{8}$ in. diameter disposed symmetrically about the axis of the cone. The filtering media consist of an annulus 41 of fine-mesh wire gauze adapted to retain water and placed adjacent to the ribs 35 and 36 and an annulus 42 of felt lying against the gauze 41. The edges 43 and 44 of the metal cone are turned inwards and towards each other so as to overlie the borders of the felt and the gauze and thus hold the filtering media in the cone.

The uppermost filtering element is placed concave side downwards with its edge 45 abutting the tubular boss 28. The next lower filtering element is placed concave side upwards with its edge 46 abutting the uppermost element. Any desired number of pairs of similarly juxtaposed filtering elements are placed on the tubular tie 30, the edge 45 of the lowest element abutting the annular facing 33 on the head 32 of the tie 30. The length of the tie is such that the filtering elements are under axial compression.

In operation, liquid enters the bowl through the inlet 11 and the port 29 and passes through the perforations 40 in the cones. Since the filtering media are spaced by the ribs 35 and 36 from the general surface of the cones, the liquid has easy access to substantially the whole of the filter surface. Filtered liquid passes through holes 47 in the interior of the tie 30 to the outlet 12.

Exhausted filter elements can be removed by removing the bowl 17 and unscrewing the tie 30, and are replaced by new elements. A bleed screw 70 provided with a sealing washer 71 is provided in the body for equalising the internal and external pressures of the filter before the filter is opened.

The embodiment shown in Figures 5 and 6 is suitable for use as a full-flow filter in the lubrication system of an internal-combustion engine.

The body of the filter is a die-cast pot 47 having an inlet socket 48 and an outlet socket 49 integral therewith. A cover 50 is also a die casting and is fastened to the body by eight studs 51 and a stud 51' co-operating with nuts 52 and a capped nut 52', the studs being disposed equidistantly around its circumference. A sealing washer 53

is provided between the body and the cover. The inlet socket 48 communicates with a bore 54 in a central boss 55 on the cover through a passage 56 and a chamber 57. The stud 51' passes through the chamber 57. A sealing washer 59 is provided between the nut 52' and the cover 50. The clamping action of this stud ensures a liquid-tight seal in the chamber 57. An even number of filter elements 60 are retained on a tubular tie 61 by flanges 62 and 63 formed at its ends. The tie has outlet holes 64 and is closed at its lower end by a cup-shaped member 65 which is slidable upon a boss 66 integral with the body 47. A helical compression spring 67 surrounds the boss 66 and presses against the flange 63 on the tie. The sides of the cup-shaped member 65 extend beyond the flange 63 and serve to prevent sideways movement of the spring 67. The spring presses the flange 62 on to an annular seating 68 on the cover and prevents the escape of liquid through longitudinal channels 69 in the boss 55. When the oil is cold or the filter elements are choked, the oil pressure drop developed across the filter causes the stack consisting of the tie and the filtering elements to move axially against the force exerted by the compression spring 67 and to open the channels 69 so that oil can pass through them to the outlet port 49. While in these circumstances the filter will pass unfiltered oil, there is substantially no risk that matter already trapped by the filter will re-enter the lubrication system, since this matter is confined by the oil pressure within the double-conical chambers inside the filter stack and is therefore not likely to work back through the tie tube into the by-passing oil stream. This filter is reconditioned by renewing the complete sub-assembly of filter elements and tie tube.

I claim:

1. A filter for liquid including a vessel, the vessel enclosing a stack of at least one pair of frusto-conical filtering elements each filtering element consisting of a pressed sheet metal perforated frusto-conical annulus having projections on its inner surface, and an annulus of sheet filtering material fitted as a lining to the inner surface of the perforated frusto-conical annulus and held in place by two annular flanges formed by unperforated borders of the perforated annulus bent inwards and towards each other so as to overlie the radially inner and outer borders of the filtering annulus, the filtering elements being pressed together base to base by means of a tie 53 consisting of a headed tubular screw engaged in an internally-screw-threaded port in said vessel, said screw passing co-axially through and fitting central apertures in the said elements, said screw furthermore having an annular abutment formed on its head and having at least one port communicating with the space within each pair of elements, a second annular abutment being formed on the vessel adjacent said internally threaded port, the annular abutments engaging the radially inner borders of the end elements of the stack, and two liquid ducts communicating respectively with the enclosed space outside the stack and with the interior of said screw.

2. A filter for liquid including a vessel, the vessel enclosing a stack of at least one pair of filtering elements, each filtering element consisting of a pressed sheet metal perforated frusto-conical annulus having concentric annular ridges formed on its concave surface and having a filtering annulus fitted as a lining and held in place

by two annular flanges on the perforated annulus overlying the radially inner and outer borders of the filtering annulus, said filtering annulus consisting of a layer of wire gauze adjacent to the perforated annulus and acting as a support for a layer of easily pliable sheet filtering material, the filtering elements being pressed together base to base by means of a tie consisting of a headed tubular screw engaged in an internally screw-threaded port in said vessel, said screw passing co-axially through and fitting central apertures in the said elements, said screw furthermore having an annular abutment formed on its head and having at least one port communicating with the space within each pair of elements, a second annular abutment being formed on the vessel adjacent said internally threaded port, the annular abutments engaging the radially inner borders of the end elements of the stack, and two liquid ducts communicating respectively with the enclosed space outside the stack and with the interior of said screw.

3. A liquid filtering element consisting of a perforated frusto-conical annulus of stiff sheet material having projections on its inner surface and an annulus of sheet filtering material fitted as a lining to the inner surface of the perforated frusto-conical annulus and held in place by two annular flanges formed by imperforated borders of the perforated annulus bent inwards and towards each other so as to overlie the radially inner and outer borders of the filtering annulus.

4. A liquid filtering element consisting of a perforated frusto-conical sheet metal annular pressing having concentric pressed annular ridges projecting on its inner surface and an annulus of sheet filtering material fitted as a lining to the inner surface of said pressing and held in place by two annular flanges formed by borders of said pressing bent inwards and towards each other so as to overlie the radially inner and outer borders of the filtering annulus.

5. An oil filtering element consisting of a perforated frusto-conical annulus of stiff sheet material having projections on its inner surface, a primary filtering annulus of wire gauze fine enough to retain water and fitted against said projections on the inner side of said stiff annulus and a secondary filtering annulus of fibrous material fitted against the inner side of said gauze annulus, said filtering annuli being held in place by two annular flanges formed integrally with the stiff annulus and projecting towards each other so as to overlie the radially inner and outer borders of the filtering annuli.

6. An oil filtering element consisting of a perforated frusto-conical sheet metal annular pressing having concentric pressed annular ridges projecting on its inner surface, a primary filtering annulus of wire gauze fine enough to retain water and fitted against said ridges on the inner side of said pressing, and a secondary filtering annulus of fibrous material fitted against the inner side of said gauze annulus, said filtering annuli being held in place by two annular flanges formed integrally with said pressing and bent inwards and towards each other so as to overlie the radially

inner and outer borders of the filtering annuli.

7. A filter for liquids including a stack of at least one pair of filtering elements, each of said elements consisting of a perforated frusto-conical annulus of stiff sheet material having projections on its inner surface and an annulus of sheet filtering material fitted as a lining to the inner surface of the perforated frusto-conical annulus and held in place by two annular flanges formed by imperforated borders of the perforated annulus bent inwards and towards each other so as to overlie the radially inner and outer borders of the filtering annulus, said elements being placed together base to base, said filter also including a tie passing co-axially through said stack and having two annular abutments engaging the radially inner borders of the end elements of the stack, a vessel enclosing the stack, and two liquid ducts communicating respectively with the space enclosed in said vessel outside said stack and with the interior of said stack, the axial spacing of said abutments being shorter than the height of said stack in its untied state, so that said elements are compressed by said tie.

8. A filter for liquids including a stack of at least one pair of filtering elements, each of said elements consisting of a perforated frusto-conical annulus of stiff sheet material having projections on its inner surface, a primary filtering annulus of wire gauze fine enough to retain water and fitted against said projections on the inner side of said stiff annulus and a secondary filtering annulus of fibrous material fitted against the inner side of said gauze annulus, said filtering annuli being held in place by two annular flanges formed integrally with the stiff annulus and projecting towards each other so as to overlie the radially inner and outer borders of the filtering annuli, said elements being placed together base to base, said filter also including a perforated tubular tie passing co-axially through said stack and having two annular abutments engaging the radially inner borders of the end elements of the stack, a vessel enclosing the stack, and two liquid ducts communicating respectively with space enclosed in said vessel outside said stack and with the interior of said tie, the axial spacing of said abutments being shorter than the height of said stack in its untied state, so that said elements are compressed by said tie.
